BULLDOZER

Edward R. Bacon, San Francisco, Calif., assignor to American Tractor Equipment Co., Oakland, Calif., a Corporation of Nevada

Application February 23, 1932. Serial No. 594,414

7 Claims. (Cl. 37—144)

This invention relates generally to devices commonly known as bulldozers, which are employed to remove large amounts of earth, as in leveling or excavating for building construction. It has 5 particular application to bulldozers constructed as attachments for standard motor tractors.

It is an object of the present invention to devise apparatus of the above character in which the scraper or other member engaging the earth can 10 be more positively controlled. In this connection the invention is characterized by the fact that power can be positively applied for lowering the scraper, as well as to raise the same.

It is a further object of the invention to devise 15 a bulldozer attachment for standard tractors which will be relatively simple but sturdy in construction, which can be readily applied to standard tractors, and in which certain operating parts will be amply housed and protected.

20 Further objects of the invention will appear from the following description in which the preferred embodiment of the invention has been set forth in detail in conjunction with the accompanying drawings. It is to be understood that 25 the appended claims are to be accorded a range of equivalents consistent with the state of the prior art.

Referring to the drawings:

Fig. 1 is a side elevational view, illustrating a 30 tractor of the track laying type having attached thereto a bulldozer incorporating the present invention.

Fig. 2 is a perspective detail illustrating the construction of the scraper bowl assembly, incorporated in my invention.

Fig. 3 is a cross sectional detail, taken along the line 3—3 of Fig. 1.

Fig. 4 is a cross sectional detail taken along the line 4—4 of Fig. 3.

40 Fig. 5 is a cross sectional detail, showing the manner of mounting and fulcruming the thrust arms to the frame of the tractor.

That form of the invention illustrated in the drawings consists of a structure 10, shown applied to a tractor 11 of the track laying type. Structure 10 includes in general a scraper bowl assembly 12, and thrust or pusher arms 13 connected to the end portions of the scraper bowl assembly and extending rearwardly along the 50 sides of the tractor 11. Each of the thrust arms 13 is preferably hollow or of skeletonized construction, being shown formed of side walls 14, and upper and lower walls 16 and 17. A convenient mode of manufacture is to form these 55 arms of steel plates welded together. Each of

these arms is also preferably tapered rearwardly, as by having the upper and lower walls 16 and 17 convergent.

The rear ends of each of the arms 13 are fulcrumed to some part of the tractor capable of applying considerable thrust, as for example the side frame members 18. Thus as shown in Fig. 5, a block 19 is secured to each frame member 18 at the side of the tractor, and this block carries a journal stud 21. Journal block 22 is fitted upon stud 21, and is in turn mounted upon the rear end of the corresponding arm 13.

While various forms of bowl assemblies can be utilized, the construction illustrated gives good results and consists of a scraper or bowl 70 member 26 formed of a curved steel plate. The lower edge portion 27 of plate 26 is adapted to dig into the formation being leveled or excavated, while the upper portion of plate 26, which is curved forwardly from the medial plate portion, serves to roll the earth forwardly as it is being displaced. Extending along the rear side of plate 26, there is another plate 28, which can be termed a torsion bowl. Plate 28 is bent to a curvature greater than that of plate 26, and has 75 its upper and lower edge portions secured to plate 26, as by means of weld connections. Plate 28 serves to impart rigidity and strength to the bowl assembly. Below plate 28, I provide another reinforcing member 29, such as a structural steel angle. The edges of angle 29 are likewise suitably secured to the rear side of plate 26, as by means of welding. Angle 29 extends substantially the full length of the bowl assembly, but plate 28 is somewhat shorter. Secured 80 to the ends of plate 26 and angle 29, as by means of weld connections, are the end plates 31.

To facilitate forming connections with arms 13, the bowl assembly also includes sockets or shoulder members 32, which are preferably hollow, and which can be formed of steel castings or of steel plates welded together. Sockets 32 are formed to fit upon the rear faces of plate 26 and angle 29, and are rigidly secured thereto and to the ends of plate 28, as by means of weld connections. Flanges 33 formed on sockets 32 facilitate bolting or riveting the bowl assembly to the flanges 34 formed upon the forward ends of arms 13.

The positioning of the structure described above, is controlled by an actuating mechanism 36, together with motion applying mechanism having points of connection with the actuating means, the structure 10 and the tractor. As shown in Fig. 4, the actuating means 36 is pref-

erably the hydraulic type, consisting of a cylinder 37 within which a double acting sliding piston is fitted. The piston is connected to an actuating rod 38, projecting from one end of the cylinder 37. The actuator is disposed within one of the arms 13, and is secured thereto by means of a pivotal connection 39, between the side walls of the arm and the cylinder 37. Hydraulic connections to the ends of the cylinder 37 are made 10 through flexible pipes 41, which extend through the upper wall 16 of the arm and which are connected with a hydraulic system provided upon the tractor. By applying hydraulic pressure to one of the flexible pipes 41, while exhausting the other, rod 38 can be positively forced in either direction.

Mounted upon the bowl of the assembly 12, by means of journal blocks 42, there is a rotatable horizontal shaft 43. Fixed to one end of shaft 43, and arranged within one of the sockets 32, there is a lever arm 44. Pivotal connection 46 serves to connect the end of this lever arm, with the forward end of rod 38 of the actuating means. Likewise fixed upon shaft 43, and arranged in spaced relationship between the sockets 32, are the lever arms 47. Rigid links 48 serve to pivotally connect the ends of lever arms 47, with brackets 49 mounted upon the sides of the main frame 51 of the tractor.

Operation of my device is believed apparent from the above description. Upon operating the hydraulic actuator 36, shaft 43 is turned a certain amount, and the scraper bowl assembly is then positioned accordingly. There will be no tendency for the scraper bowl assembly to ride upon the formation being leveled or excavated, because the motion applying means by which the position of the bowl assembly is determined is relatively rigid. Furthermore, by control of the actuator, the bowl assembly can be positively forced downwardly under power, instead of merely relying upon the weight of the bowl assembly and associated parts. The structure formed by the bowl assembly and the side arms 13 is relatively rigid and is capable of withstanding severe stresses without breakage or permanent deformation. Likewise the mounting of the actuator, and certain other moving parts, within one of the hollow arms 13, adequately protects these parts against breakage, and prevents contact with masses of earth being leveled or excavated.

I claim:

1. In a bulldozer attachment for tractors, a structure including a scraper adapted to be positioned in front of the tractor, and a pair of thrust arms secured to the end portions of the scraper and extending rearwardly along the sides of the tractor, said arms being adapted to be fulcrumed upon the tractor, actuating means mounted upon said structure and housed within one of said arms, and motion transmitting means having points of connection with the actuating means, said structure, and the tractor, said last means including links and levers whereby said actuating means can exert a positive force between the tractor and said structure to urge said structure downwardly.
2. In a bulldozer attachment for tractors, a structure including a scraper adapted to be positioned in front of the tractor, and a pair of thrust arms secured to the end portions of the scraper and extending rearwardly along the sides of the tractor, said arms being adapted to

be fulcrumed upon the tractor, actuating means mounted upon said structure and housed within one of said arms, a horizontal shaft journaled to said structure and arranged adjacent the forward end of the same, rigid motion transmitting means connecting said shaft with said actuating means, and rigid motion transmitting means connecting said shaft with the forward portion of the tractor, whereby said actuating means can apply positive forces to said structure to raise or lower the same.

3. In a bulldozer attachment for tractors, a structure including a scraper adapted to be positioned in front of the tractor and a pair of thrust arms secured to the end portions of the scraper and extending rearwardly along the sides of the tractor, said arms being adapted to be fulcrumed upon the tractor, actuating means mounted upon one of said arms, a horizontal shaft journaled to said structure adjacent the forward end of the same, a lever fixed to said shaft, a rigid rod connecting said lever with said actuating means, another lever fixed to said shaft, and a rigid link connecting said last named lever with the forward portion of the tractor.

4. In a bulldozer attachment for tractors, a structure including a scraper adapted to be positioned in front of the tractor and a pair of thrust arms secured to the end portions of the scraper and extending rearwardly along the sides of the tractor, said arms having their rear end portions adapted to be fulcrumed upon the tractor, actuating means mounted upon one of said arms, a horizontal shaft journaled to said structure adjacent the forward end of the same, a lever fixed to said shaft, a rigid motion transmitting rod connecting said lever with said actuating means, a pair of additional levers fixed to said shaft and arranged in spaced relationship between said arms, and a pair of rigid links serving to connect said last mentioned levers with the forward portion of the tractor.

5. In a bulldozer attachment for tractors, a structure including a scraper adapted to be positioned in front of the tractor and a pair of hollow thrust arms secured to the end portions of the scraper and extending rearwardly along the sides of the tractor, the rear end portions of said arms being adapted to be fulcrumed upon the tractor, hydraulic actuating means mounted within one of said arms, said actuating means including a cylinder, a piston slidably fitted within the cylinder, and a piston rod secured to the piston and extending from one end of the cylinder, means for pivotally mounting said cylinder to said one arm, and motion transmitting means having points of connection with the actuating means, said structure and the tractor, whereby said structure can be raised or lowered upon operation of said actuating means.

6. In a bulldozer attachment for tractors, a structure including a scraper adapted to be positioned in front of the tractor and a pair of hollow thrust arms secured to the end portions of the scraper and adapted to extend rearwardly along the sides of the tractor, the rear ends of said arms being adapted to be fulcrumed upon the tractor, actuating means disposed within one of said arms, said actuating means including a hydraulic cylinder, a piston slidably fitted within the cylinder, and a piston rod secured to the piston and extending from one end of the cylinder, means for pivotally mounting said cylinder to said one arm, a horizontal shaft journaled to said structure adjacent the forward end of the same, a lever fixed

to said shaft and positioned within said one arm, said lever having pivotal connection with said piston rod, an additional lever fixed to said shaft, and a rigid link serving to pivotally connect said 5 last mentioned lever with the forward portion of the tractor.

7. In a bulldozer attachment for tractors, a structure including a scraper bowl assembly adapted to be positioned in front of the tractor 10 and a pair of thrust arms secured to the end portions of the assembly and extending rearwardly

along the sides of the tractor, said assembly including a curved scraper plate, a curved plate forming a torsion bowl secured upon the rear side of the scraper plate and sockets secured to the end portions of the torsion bowl member and serving as a means for mounting the assembly upon the forward ends of said arms, and means for raising and lowering said structure with respect to the tractor.
